CLAIM

The ornamental design for a snap-on cover for striker, as shown and described.

DESCRIPTION

FIG. 1 is a top perspective view of a first embodiment of the snap-on cover for striker;

FIG. 2 is a top plan view thereof;

FIG. 3 is a left side view thereof;

FIG. 4 is a right side view thereof;

FIG. 5 is a top end view thereof;

FIG. 6 is a bottom end view thereof.

FIG. 7 is a top perspective view of a second embodiment;

FIG. 8 is a top plan view thereof;

FIG. 9 is a left side view thereof;

FIG. 10 is a right side view thereof;

FIG. 11 is a top end view thereof; and,

FIG. 12 is a bottom end view thereof.

The broken lines present in the drawings are included for the purpose of illustrating portions of the article which form no part of the claimed design.

1 Claim, 12 Drawing Sheets
